J. C. BRADSHAW

RAILROAD CROSSING

Filed Sept. 10, 1927

FIG. 1.

UNITED STATES PATENT OFFICE.

JULIUS CAESAR BRADSHAW, OF MOBILE, ALABAMA.

RAILROAD CROSSING.

Application filed September 10, 1927. Serial No. 218,739.

This invention relates to a railroad crossing and it is an improvement on the crossing shown in my Patent No. 989,759 dated April 18, 1911, and it is an object of the present invention to provide a crossing wherein the requisite switching operations are rendered easier for the cars than in connection with the arrangement shown in my former patent.

The invention consists in the details of construction and in the combination and arrangement of the several parts of my improved railroad crossing whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:

Figure 1 is a diagrammatic view illustrating a railroad crossing constructed in accordance with an embodiment of my invention; and

Fig. 2 is an enlarged fragmentary view illustrating diagrammatically a portion of the crossing as embodied in Figure 1.

As disclosed in the accompanying drawing, parallel intersecting main tracks N, S, E and W are shown and in each set of tracks is provided a three throw switch 1. These switches control the movement of the cars over the tracks 2 which connect the N and S tracks with the E and W tracks respectively, two sets of such switches being employed and extending in opposite directions from each of the main tracks.

Each of the tracks 2, as for example, the one leading from the E track to the S track is provided adjacent to the E track and to the S track with the single throw switch 3 permitting a car to travel over the track 2 from the E track to the S track or over the track 4 from the E track to the N track and in a similar manner at each of the four sides of the crossing.

Assuming that there are two cars upon the E track, one of which is a "through" car on the S track and the other is to be switched upon the west bound track on its return trip, the switch 1 is with respect to

the track 2 opened and such car moves over the track 2 upon the south bound track and continues in this direction. The second car after the first car has passed beyond the switches 1 and 3 is moved over the track 60 4 by opening the switch 3. This second car, therefore, moves upon the north bound track beyond the switch 1 arranged therein. Upon requisite throw of the switch 1 the car passes over the track 2 leading from the N track and upon opening the switch 3 in such track 2 the car will pass over the track 4 to the west bound track, thus the car is reversed and continues upon its return trip. This operation applies to a car moving in 70 any direction.

With my improved crossing it will then be seen that a car may be switched from any one of the main intersecting tracks onto either of the other main tracks running at 75 right angles thereto, thus avoiding delay in the movement of the cars over the crossing and also permit of the switching of two or more cars at one time.

The various switches may be of any preferred construction and the tracks at the intersecting points are connected and braced in the usual manner.

My improved crossing as herein embodied includes twenty switching tracks at the intersection of the main tracks of the system and these tracks may be arranged and installed with economy and permits of the handling of a large number of cars with convenience and facility and particularly 90 to avoid locking or congestion.

From the foregoing description it is thought to be obvious that a railroad crossing constructed in accordance with my invention is particularly well adapted for use 95 by reason of the convenience and facility with which it may be assembled and operated, and it will also be obvious that my invention is susceptible of some change and modification without departing from the 100 principles and spirit thereof and for this reason I do not wish to be understood as limiting myself to the precise arrangement and formation of the several parts herein shown in carrying out my invention in practice except as hereinafter claimed.

I claim:

A railroad crossing comprising parallel intersecting main tracks, a three throw switch located in each main track on each 110

side of the intersecting points, a switching track connecting each one of the switches in each of the main tracks with a switch in one of the intersecting trackways, a switching track connecting said first named switch with a switch in the second intersecting trackway at the opposite side of the points of intersection, and a switching track con-

necting one of each pair of first named switching tracks with an intersecting main track parallel to the main track with which the second of said pair of switching tracks connect. 10

In testimony whereof I hereunto affix my signature.

JULIUS CAESAR BRADSHAW.
